FIREARM

Clair W. Wadsworth, Fulton, N. Y., assignor to
Hunter Arms Co., Inc., Fulton, N. Y., a corpora-
tion of New York

Application May 16, 1934, Serial No. 725,977

7 Claims.

(Cl. 42—1)

This invention relates generally to fire arms and particularly to gas guns, and has for its object a firing mechanism particularly adapted for guns of this type in the form of policemen's billys or clubs, and has for its object a particularly simple and efficient firing and trigger mechanism and safety mechanism which consists of a few compactly arranged parts.

It further has for its object a firing, trigger and safety mechanism wherein the trigger is shifted transversely of the hammer of the firing mechanism to unlock the safety mechanism and vice-versa.

It further has for its object a trigger which is exposed on opposite sides of the grip handle of the fire arm or billy and operable from one side to disengage it from safety position and from the other side to retract and release the hammer when out of safety position.

It further has for its object an arrangement of the trigger mechanism wherein when in safety position, the outside of the grip handle is practically smooth or unobstructed from projecting parts of the trigger mechanism.

It further has for its object a particularly simple assembly of the parts associated with the grip handle.

Other objects will appear throughout the specification.

The invention consists in the novel features and in the combinations and constructions hereinafter set forth and claimed.

In describing this invention, reference is had to the accompanying drawing in which like characters designate corresponding parts in all the views.

Figure 1 is an elevation of this fire arm with the handle and barrel separated and the handle shown in section.

Figure 2 is a fragmentary elevation illustrating the slot in which the trigger moves, the trigger being shown in its retracted position just prior to being released.

Figure 3 is a fragmentary view illustrating in elevation the opposite side of the grip handle from that shown in Figure 2.

This fire arm or billy comprises a body including a grip handle and a barrel detachably mounted on one end of the grip handle and in line therewith, firing mechanism located within the grip handle including a spring pressed hammer and trigger mechanism including a trigger extending transversely through the hammer and movable therewith and also shiftable endwise transversely of the hammer and the handle in

order to release it from safety position to permit the operation of the trigger to fire the gun or to replace the trigger in safety position and lock it from being operated.

1 designates the grip handle and 2 the barrel constituting the body of the gun. The grip handle is formed with a threaded countersink or recess 3 at its breech end which receives a reduced threaded portion 4 at the inner end of the barrel 2, the threads forming means for detachably securing the barrel to the handle, the breech being detachable for the purpose of removing and inserting the cartridge 5.

The barrel is a metal tube with annular collars 6, 7 at its ends between which are snugly placed 15 fibrous material, as leather or raw-hide. The fibrous material is usually in the form of coils or rings.

The handle 1 includes a metallic body portion 8 and an internal tubular portion 9 which fits into a bore 11 near the inner end of the handle at the inner end of the recess 3 flush with the surface 3a of the recess at the inner ends of the threads, the surface 3a being in effect an internal annular shoulder at the bottom of the recess. 20

12 is a breech block or plug threading into the upper end of the tube 9 and having an annular flange or head 13 overlying the end of the tube and the annular shoulder 3a, this plug forming the bottom of the cartridge chamber against which the cartridge thrusts. It is formed with a passage 14 for a firing pin 15. The tube 9 is threaded at its lower end and is provided with an annular flange or collar 16 threaded thereon which is opposed to the lower end of the body 8. A covering of raw-hide or leather 17 is interposed between the collar 16 and the lower end of the body 8. A cap 18 threads on the threaded end of the tube 9 against the collar. 30

The firing mechanism comprises a hammer 21 movable rectilinearly in the cavity formed by the tube 9 within the body 8, this being cylindrical in general form and slidably fitting the tube 9, the firing pin 15 being carried by the hammer at one end thereof and being preferably integral therewith. 40

22 is the hammer spring. 23 designates the trigger, this being carried by the hammer and slideable or shiftable transversely thereof in a passage 24 provided in the hammer and when in one of its shifted transverse positions, is interlocked with the grip handle or body 8 thereof to hold it from movement intended to operate the hammer, and when in the other of its shifted positions, is out of safety position so that the 50 55

trigger can be operated to actuate the hammer. The trigger is held in either one of its shifted positions by impositive locking means, here shown, as a poppet 25 coacting with recesses or 5 grooves 26 formed in the trigger, the poppet being pressed by a spring 27. The poppet and spring are located within a lengthwise chamber 28 formed in the hammer and opening through the lower end thereof, the spring being inter- 10 posed between the poppet and a spring abutment 29 closing the lower open end of the passage of the hammer. The hammer spring 27 thrusts at its inner end against this abutment 29 and at its outer end against the cap 18.

15 The billy is provided with a strap 31 for carrying it extending through a hole in the cap and being anchored to the spring by a key 32 extending through the strap and between the end coils of the spring 22.

20 The body 8 is provided with a lengthwise slot 33 in one side thereof for permitting the operation of the trigger to retract and release the hammer and also with an opening 34 in the side thereof diametrically opposite the slot, this opening being in the bottom of a depression 35 in the body 8 of the grip handle. The trigger is provided with heads 36 and 37 at its opposite ends and the slot 33 is provided with an enlargement 38 for receiving the head 36 when the trigger is 25 set in safety position, this enlargement 38 being located in alignment with the opening 34. When the trigger is shifted transversely of the hammer in one direction, the head 37 enters the opening 34, while the head 36 enters the enlargement 38, 30 thus the trigger and hammer are locked against retracting movement or locked in safety position and when in such position, the heads are substantially flush with the outer peripheral surface of the grip handle, the head 37 being located in 35 the recess 35 and the head 36 in the enlargement 38. The tube 9 is formed with slots 40, 41 alined with the slot 33 with its enlargement and the opening 34.

To unlock the trigger from safety position, 45 the head 37 is pressed through the opening 34 to the inside of the handle into the slot 41, thus shifting the trigger 24 transversely of the hammer so that the poppet is forced out of one groove and enters the other groove 26, and the head 36 50 moves out of the enlargement 38. The enlargement 38 is slightly offset laterally relative to the median line of the slot 33 and hence upon pressing laterally on the head 36, the trigger 24 is brought into alignment with the slot 33 in which 55 position it can be slid along retracting the hammer against the spring 22. When retracted to nearly its fullest extent, the head 36 may be released, whereupon the hammer is impelled forwardly causing the firing pin to fire the cap of the cartridge. During the lateral manipulation 60 of the trigger to carry the trigger in line with the slot 33, the hammer rocks slightly and the slot 41 in the sleeve 9 in which the head 37 slides during the operation of the hammer is wide 65 enough to permit this rocking movement. To reset the trigger in safety position, it is merely necessary to shift it until the head 37 again passes through the opening 34 above the bottom of the depression 35. To reload, the barrel 2 is 70 detached from the grip handle, the old cartridge allowed to fall out, a new cartridge placed in the barrel, and the barrel replaced.

When the trigger is in safety position, the outside of the grip handle is substantially smooth so 75 that the billy can be used as a club without danger

of unintentionally firing the cartridge. When it is desired to fire the cartridge, the trigger is readily released from its safety position by depressing the head 37 by the index finger of the hand gripping the handle and the trigger can 5 then be retracted by the thumb.

What I claim is:

1. In a fire arm, the combination with a grip handle having an internal cavity, a barrel in line with the grip handle, the barrel of the handle being formed with a cartridge chamber, and firing mechanism in the cavity including a spring pressed hammer movable lengthwise of the cavity; of trigger mechanism including a trigger extending transversely through the hammer and shiftable transversely relative thereto, the handle having a lengthwise slot through which one end of the trigger extends for permitting pulling back and releasing of the hammer, and the handle and the trigger being also provided with means coacting to prevent retraction of the hammer, when the trigger is in one of its transverse positions and permit retraction of the hammer, when the trigger is shifted into the other of its transverse positions.

2. In a fire arm, the combination with a grip handle having an internal cavity, a barrel in line with the grip handle, the barrel of the handle being formed with a cartridge chamber, and firing mechanism in the cavity including a spring pressed hammer movable lengthwise of the cavity; of trigger mechanism including a trigger extending transversely through the hammer and shiftable transversely relative thereto, the handle having a lengthwise slot through which one end of the trigger extends for permitting pulling back and releasing of the hammer, and the handle and the trigger being also provided with means coacting to prevent retraction of the hammer, when the trigger is in one of its transverse positions and permit retraction of the hammer when the trigger is shifted into the other of its transverse positions, and impositive locking means for holding the trigger in either of its transverse positions.

3. In a fire arm, the combination with a grip handle having an internal cavity, a barrel in line with the grip handle, the barrel of the handle being formed with a cartridge chamber, and firing mechanism in the cavity including a spring pressed hammer movable lengthwise of the cavity; of trigger mechanism including a trigger extending transversely through the hammer and shiftable transversely relative thereto, the handle having a lengthwise slot through which one end of the trigger extends for permitting pulling back and releasing of the hammer, and the handle and the trigger being also provided with means coacting to prevent retraction of the hammer, when the trigger is in one of its transverse positions and permit retraction of the hammer when the trigger is shifted into the other of its transverse positions, and impositive locking means for holding the trigger in either of its transverse positions, said locking means being carried by the hammer.

4. In a fire arm, the combination with a grip handle having an internal cavity, a barrel in line with the grip handle, the barrel of the handle being formed with a cartridge chamber, and firing mechanism in the cavity including a spring pressed hammer movable lengthwise of the cavity; of trigger mechanism including a trigger extending transversely through the hammer and 70

- shiftable transversely relatively thereto, the handle having a lengthwise slot through which one end of the trigger extends for permitting pulling back and releasing of the hammer, and the handle and the trigger being also provided with means coacting to prevent retraction of the hammer, when the trigger is in one of its transverse positions and permit retraction of the hammer when the trigger is shifted into the other of its transverse positions, and a spring pressed poppet carried by the hammer and coacting with the trigger to hold it in either one of its transverse positions.
5. In a fire arm, the combination with a body including a grip handle having an internal cavity and a barrel in line with the grip handle, the body being formed with a cartridge chamber, and firing mechanism in the cavity of the grip handle including a spring pressed hammer movable lengthwise of the cavity; of trigger mechanism including a trigger extending transversely through the handle and shiftable transversely relatively thereto, the handle having a lengthwise slot into which one end of the trigger extends, and with an opening diametrically opposite one end of the slot, the trigger having heads at its ends and the slot having an enlargement at one end for receiving the corresponding head of the trigger, the head at the other end of the trigger entering said opening for locking the trigger from movement along the slot, the trigger being shiftable to carry the last-mentioned head inwardly out of the opening and for carrying the head at the opposite end of the trigger out of the enlargement of the slot, whereby the trigger may be shifted axially along the slot to retract the hammer.
10. Other of its transverse positions, and a spring pressed poppet carried by the hammer and coacting with the trigger to hold it in either one of its transverse positions.
15. In a fire arm, the combination with a body including a grip handle having an internal cavity and a barrel in line with the grip handle, the body being formed with a cartridge chamber, and firing mechanism in the cavity of the grip handle including a spring pressed hammer movable lengthwise of the cavity; of trigger mechanism including a trigger extending transversely through the hammer and shiftable transversely relatively thereto, safety means for holding the trigger from movement when the trigger is in one of its transverse positions, the trigger being operable transversely to release it from the safety means, whereby the trigger is operable to retract the hammer.
20. In a fire arm, the combination with a body including a grip handle having an internal cavity and a barrel in line with the grip handle, the body being formed with a cartridge chamber, and firing mechanism in the cavity of the grip handle including a spring pressed hammer movable lengthwise of the cavity; of trigger mechanism including a trigger extending transversely through the hammer and shiftable transversely relatively thereto, safety means for holding the trigger from movement when the trigger is in one of its transverse positions, the trigger being operable transversely to release it from the safety means, whereby the trigger is operable to retract the hammer, and a spring pressed poppet carried by the hammer and coacting with the trigger for frictionally holding it in either of its transverse positions.
25. In a fire arm, the combination with a body including a grip handle having an internal cavity and a barrel in line with the grip handle, the body being formed with a cartridge chamber, and firing mechanism in the cavity of the grip handle including a spring pressed hammer movable lengthwise of the cavity; of trigger mechanism including a trigger extending transversely through the hammer and shiftable transversely relatively thereto, safety means for holding the trigger from movement when the trigger is in one of its transverse positions, the trigger being operable transversely to release it from the safety means, whereby the trigger is operable to retract the hammer, and a spring pressed poppet carried by the hammer and coacting with the trigger for frictionally holding it in either of its transverse positions.
30. In a fire arm, the combination with a body including a grip handle having an internal cavity and a barrel in line with the grip handle, the body being formed with a cartridge chamber, and firing mechanism in the cavity of the grip handle including a spring pressed hammer movable lengthwise of the cavity; of trigger mechanism including a trigger extending transversely through the hammer and shiftable transversely relatively thereto, safety means for holding the trigger from movement when the trigger is in one of its transverse positions, the trigger being operable transversely to release it from the safety means, whereby the trigger is operable to retract the hammer, and a spring pressed poppet carried by the hammer and coacting with the trigger for frictionally holding it in either of its transverse positions.
35. In a fire arm, the combination with a body including a grip handle having an internal cavity and a barrel in line with the grip handle, the body being formed with a cartridge chamber, and firing mechanism in the cavity of the grip handle including a spring pressed hammer movable lengthwise of the cavity; of trigger mechanism including a trigger extending transversely through the hammer and shiftable transversely relatively thereto, safety means for holding the trigger from movement when the trigger is in one of its transverse positions, the trigger being operable transversely to release it from the safety means, whereby the trigger is operable to retract the hammer, and a spring pressed poppet carried by the hammer and coacting with the trigger for frictionally holding it in either of its transverse positions.
